H. DALE

WRENCH

Filed May 26, 1923

INVENTOR

Harry Dale

Mason, Fennisch & Lawrence
ATTORNEYS

UNITED STATES PATENT OFFICE.

HARRY DALE, OF SEATTLE, WASHINGTON.

WRENCH.

Application filed May 26, 1923. Serial No. 241,781.

To all whom it may concern:

Be it known that I, HARRY DALE, a citizen of the United States, residing at Seattle, in the county of King and State of Washington, have invented certain new and useful Improvements in Wrenches; and I do hereby declare the following to be a full, clear, and exact description of the invention, such as will enable others skilled in the art to which 10 it appertains to make and use the same.

This invention relates to improvements in wrenches, and more particularly to pipe wrenches having relatively adjustable jaws.

It is an object of the invention to mount 15 the movable jaw in such a manner that it may be tilted with respect to the opposite jaw, so as to enable the jaws to be quickly passed over the object to be turned, the tilting movement being independent of the 20 means for varying the fixed opening between the jaws.

It is a further object of the invention to provide a wrench wherein the turning strain shall be received in part on the back of the 25 fixed jaw and in part on the handle of the wrench.

The above and other objects of the invention will appear from the detailed description taken in connection with the accompanying sheet of drawing forming a part of 30 the specification.

Referring to the drawings, Fig. 1 is a side elevation of the improved wrench;

Fig. 2 is a cross section on line 2—2 of 35 Fig. 1, and

Fig. 3 is a section taken longitudinally through the wrench.

In the drawings, numeral 1 indicates the movable jaw and 2 the fixed jaw. The jaw 40 1 has a shank 3 and the jaw 2 has a handle extension 4, the jaw 2 having a slot 5 extending therethrough, which is continued as a trough 6 in the handle part 4. The trough is substantially the same as the length of the shank 3, and the handle beyond the end of 45 the trough is preferably reduced in thickness.

The shank 3 of the jaw 1 is slidably mounted in a block 7. The adjustment of 50 the shank or jaw is controlled by a screw 8, which is turnably mounted within the block, and which engages with teeth 9 in the shank.

The connection between the shank and block preferably takes the form of a tongue 55 and groove connection, the shank being grooved on both sides as at 10 for the recep-

tion of tongue-like members 11, which extend upwardly from the block. The trough 6, in which the shank normally seats preferably flares outwardly, as shown in Fig. 2, so as to simplify the tongue and groove connection.

The block 7 is provided with a finger-like extension 12, which extends into the slot 5 in the jaw 2, and is pivoted near the front of the jaw on a pivot 13. Within the slot is also a spring 14, which tends to press the block 7 toward the handle 4 and to hold the shank 3 against the bottom of the trough 6.

The pivot 13 of the block is set forwardly 70 of the end of the trough in the back of the handle, the latter being flared from a point adjacent said pivot toward said back. By reason of this construction, the block and jaw therein may freely swing about the pivot 75 13 as will be readily understood.

The back of the jaw 2 is rounded as at 15, and the block 7 has its adjacent end shaped to conform to the back of the jaw 2, it being contemplated that the pull or strain 80 between the jaws shall be transmitted from the block 7 to the back of the jaw 2. The pin 13 merely serves to confine the block 7 to its arcuate movement about the back of the jaw 2.

The maximum width of the block 7 is no greater than the thickness of the jaw 2, and the parts bearing against the back of the jaw are therefore in the nature of shoulders on either side of the finger-like extension 12. 90 The screw 8 is preferably of less diameter than the width of the block 7, so that the same will be less liable to be accidentally turned when the wrench is being used.

From the above, it will be seen that there 95 has been provided a wrench which is simple and sturdy in construction and in which the turning strain is received on the parts of the wrench most adapted to receive it. The action tending to separate the jaws is received 100 by the handle 4 in the bottom of the trough 6 thereof. By pivoting the block 7 to the fixed jaw near the front working face thereof, relative angularity between the jaws is 105 readily obtained during the preliminary operation of placing the wrench over the object to be turned.

What I claim is:

In a wrench, the combination of a block 110 having inwardly directed guide ways, a movable jaw having longitudinally extending seats into which said ways are seated, a

screw in said block for moving said jaw with respect to said block, a handle jaw having a trough in which the other jaw is slidable by means of said screw and having an open 5 pocket in said jaw, an extension on said block entered in said pocket and pivoted therein, whereby said block and jaw therein may

swing on the pivot of said block, said handle having an outwardly flaring seat along the outer edges of the trough within which the 10 inwardly directed guide ways of said block may seat.

In testimony whereof I affix my signature.
HARRY DALE.
